CLAIM

The ornamental design for a panel fastener or the like, as shown and described.

DESCRIPTION

FIG. 1 is a top plan view of a panel fastener or the like, showing our new design;
FIG. 2 is a bottom plan view thereof;
FIG. 3 is a front elevational view thereof;
FIG. 4 is a side elevational view taken from the right of FIG. 3;
FIG. 5 is a rear elevational view thereof;
FIG. 6 is a cross-sectional view thereof, the panels being shown in broken lines for illustrative purposes only
FIG. 7 is a top and front perspective view thereof.
